UNITED STATES PATENT OFFICE.

ERNEST A. WALKER, OF NEWARK, NEW JERSEY.

DESIGN FOR A TWO-LIGHT ARM FOR LIGHTING FIXTURES.

Application filed November 6, 1923. Serial No. 7,690. Term of patent 7 years.

To all whom it may concern:

Be it known that I, ERNEST A. WALKER, a citizen of the United States, residing at 762 Summer Avenue, Newark, in the county of Essex and State of New Jersey, have invented a new, original, and ornamental Design for a Two-Light Arm for Lighting Fixtures, of which the following is a specification, reference being had to the accompanying drawing, forming part thereof.

Fig. 1 is a bottom view of a two-light arm for lighting fixtures, showing my new design

and Fig. 2 and Fig. 3 are front and top views, respectively, thereof.

I claim:

The ornamental design for a two-light arm for lighting fixtures, as shown.

In witness whereof, I hereunto subscribe my name, as attested by the two subscribing witnesses.

ERNEST A. WALKER.
